[57] CLAIM

The ornamental design for package for confectionery products, as shown and described.

DESCRIPTION

FIG. 1 is a front elevation of a package for confectionery products showing my new design, the rear side being a mirror image thereof;

FIG. 2 is a left side elevation thereof, the right side being a mirror image thereof;

FIG. 3 is a top plan view thereof; and

FIG. 4 is a perspective view thereof.

The bottom is plain and unornamented.

FIG. 1

FIG. 2

FIG. 3

FIG. 4
